UNITED STATES PATENT OFFICE.

WILLIAM E. MOORE, OF CHICAGO, ILLINOIS, ASSIGNOR, BY MESNE ASSIGNMENTS, TO INTERNATIONAL EARTH-BORING MACHINE CORPORATION, A CORPORATION OF DELAWARE.

EARTH-BORING MACHINE.

1,409,394.

Specification of Letters Patent. Patented Mar. 14, 1922.

Application filed April 5, 1919. Serial No. 287,739.

To all whom it may concern:

Be it known that I, WILLIAM E. MOORE, a citizen of the United States, residing at Chicago, in the county of Cook and State 5 of Illinois, have invented certain new and useful Improvements in Earth-Boring Machines, of which the following is a specification.

This invention relates to earth boring machines.

It is particularly applicable to earth boring machines of the mobile type.

The earth boring machine in which the invention has been embodied comprises, in 15 general, a vehicle upon which a turntable is mounted. A tiltable auger tower is mounted on one side of the turntable and adjacent the tower is a power driven rotatable and longitudinally movable auger shaft for 20 carrying and operating the boring auger.

An earth boring machine of this general type is set forth in my copending application Serial No. 252,994, filed September 7, 1918.

25 An object of this invention is to provide a shaft drive for raising and lowering a tiltable auger shaft.

Another object is to provide a shaft power drive which may raise or lower the auger at 30 any angle of inclination of the auger shaft.

Other objects and advantages will appear from the specification and claims.

An embodiment of the invention is illustrated in the accompanying drawings.

35 In the drawings—

Fig. 1 represents a side elevation of the rear part of a machine constructed to embody my invention.

40 Fig. 2 is a top plan view of the parts shown in Fig. 1.

Fig. 3 is a longitudinal section taken substantially on line 3—3 of Fig. 4 and line 3 of Fig. 2.

45 Fig. 4 is a horizontal section taken substantially on line 4—4 of Fig. 1, the parts being shown on a slightly enlarged scale.

Fig. 5 is a section taken on line 5—5 of Fig. 4.

50 Fig. 6 is a section taken substantially on line 6—6 of Fig. 5.

The invention is shown embodied in an earth boring machine of the general type set forth in the above mentioned application, Serial No. 252,994. This machine includes

the main frame 10 supported for the purpose of portability on wheels 11. The supporting frame 12, in the form of a turntable, is carried by main frame 10 through suitable antifriction bearings 13. This supporting frame includes suitable longitudinal members 14 and transverse members 15. A suitable motor, not shown, is supported on said frame. At the rear end of the supporting frame is pivotally mounted the auger supporting tower or frame, this general combination and construction of the parts being broadly the same as shown and described in my said prior application.

Driving belt 16 transmits power from the motor to a driving pulley 17 on a driving shaft 18 which extends transversely across an intermediate part of the supporting frame 12. A counter or driven shaft 19 is arranged in parallel relation to the driving shaft 18. Intermeshing gears 20 and 21 are loosely mounted on shafts 18 and 19 on one side of the frame and are adapted to be connected to their respective shafts by means of clutches 22 and 23, respectively. The clutches are so arranged that when one of the gears is clutched to its shaft the other gear will be loose on its shaft. These clutches are operated by a lever 24 connected by link 25 to operator's lever 26. Lever 24 is pivotally mounted with reference to the frame on a pivot 27. These shafts 18 and 19 are also operatively connected by means of a chain 28 engaging a sprocket 29 on shaft 18 and a larger sprocket 30 on shaft 19. On one end of the shaft 18 I provide a sprocket 31 having a chain 32 for driving a sprocket 33 on a shaft 34 to be presently described. A clutch 35 is actuated by an operator's lever 36 so as to operatively connect sprocket 31 with shaft 18 for the purpose of driving shaft 34.

A sprocket 37 is mounted to rotate with gear wheel 21 and drive a chain 38 to drive a sprocket 39 on a shaft 40. A bevel gear 41 is secured near the other end of this shaft 100 and a sleeve 42 is loose on said shaft. Extending laterally from sleeve 42 is a boss 43 which forms a bearing for the end of an inclined shaft 44, which has on its lower end, a bevel gear 45 which meshes with bevel gear 41 on shaft 40. Bevel gear 45 is held in place by means of spring clips 46, the ends of which engage in a groove formed in

the hub of bevel gear 45, see the dotted line disclosure in Fig. 3 of the drawing. This inclined shaft 44 is provided with a longitudinally extending spline or key-way 47 to receive a key or feather 48, connecting a bevel gear 49 in slidable relation thereto. This bevel gear 49 is rotatably connected to a box 50 by means of spring clips 51 engaging in a groove 52 formed in the hub of gear wheel 49. Thus box 50 is likewise slidable relative to shaft 44. This box 50 forms the journal or bearing for a short transverse shaft 53. To shaft 53 is keyed a bevel gear 54 meshing with bevel gear 49. Shaft 53 is journaled in the bracket members 55 depending from auger supporting frame or tower. Between these bracket members 55 I secure to the shaft 53 a sprocket 56 which is operatively connected by means of a chain 57 with a sprocket 58 at the top of the auger supporting frame or tower.

This auger supporting frame or tower is designated generally by the reference character 59 and includes four elongated and vertically extending angle irons 60 which are arranged to form a substantially rectangular frame and which slidably receive a sliding head 61 on an auger shaft 62. The auger shaft 62 is secured to and depends from the head 61 and has a suitable auger or boring tool 63 connected to the lower end thereof. This auger shaft 62 is rotated to drive the auger 63 by means of a bevel gear train 64 enclosed in a gear box 66 and driven by shaft 34. The sliding head 61 is suitably connected to the sprocket chain 57 whereby movement of the sprocket will cause the auger to be raised and lowered, as is well understood.

40 Auger tower 59 is pivotally mounted with reference to the supporting frame 12. It is supported on one side by means of shaft 34 and on the other side by means of a trunnion 65 which is journaled in a bearing on the elongated side frame member 14 of frame 12. Any suitable means may be utilized for moving the auger tower 59 on its pivot so as to bore the hole at various angles relative to the main frame, one form of such 45 means being illustrated in my said prior application.

The auger tower is held against lateral swaying movement by means of brace members 67 which are connected near the top 55 thereof and extend outwardly to the outer side frame members 14 of frame 12, having a pivotal connection or bearing therewith, as shown at 68, Figs. 1 and 2. The auger tower is also provided with bracing and holding 60 members extending longitudinally of the frame, these members comprising rods 69 pivotally mounted, as at 70, to the intermediate longitudinal members 14 of the frame 12 and slidably passing through 65 sleeves 71 provided on brackets 72 which are

pivoted to tower 59. Set screws 73 provide means for holding the tower in adjusted inclined position.

It is therefore seen that I have provided a shaft drive for raising and lowering the 70 auger to and from operative position and feeding the same, which may be operated regardless of the inclination of the auger tower 59, it being seen that gear 48 and box 50 are slidable along shaft 44 and that the 75 same has a pivotal bearing in the boss 43 on the sleeve 42, which may turn on shaft 40.

In connection with this mechanism I also provide a derrick or frame construction which includes a hollow post or pipe 74 80 through which passes an anchor rod 75, this rod also passing through the main frame 10 and forming the pivot or center on which the frame 12 turns relative to the main frame 10. This pipe 74 passes through a stationary socket or supporting member 76 and may turn therein. This member 76 is held in position by means of radiating brace rods 77 which are provided with turn buckles 78 whereby they may be adjusted as desired. 90 The outer ends of members 77 are secured to the outside longitudinal members 14 of the frame 12. The top end of hollow post 74 is braced by a strut or support 79. To this post 74 is pivotally connected a crane or derrick arm 80, the outer end of which is connected to the upper end of post 74 by means of a bracing link 81. This crane or derrick has the usual pulley 82 through which passes a cable 83 which is wound upon a drum or 100 windlass 84 which may be driven in any desired manner.

Having described my invention, what I claim is:—

1. An earth boring machine having a supporting frame; an auger tower tiltably mounted on said supporting frame; an auger shaft longitudinally movable relative to the tower; and means for moving the auger shaft longitudinally of the tower including a relatively stationary driving shaft journaled on the supporting frame, a driven shaft journaled on the auger tower and movable therewith relative to the driving shaft, a relatively extensible and contractible counter-shaft interconnecting the driven and driving shafts and contractible and extensible with the tilting of the tower, and means actuated by the driven shaft and connected to the auger shaft to raise and lower the 110 115 auger shaft.

2. An earth boring machine including in combination a supporting frame, an auger tower pivotally mounted on said supporting frame, means for raising and lowering the 125 auger in the tower, including a shaft connected to said auger tower and movable therewith, a driving shaft and connections between said driving shaft and said shaft on the auger tower, said connections in- 130

cluding a shaft movably arranged in relation to said driving shaft and having operative connection therewith, a gear movably mounted on said movable shaft and having operative connection with the shaft on said auger tower and movable therewith when the auger tower is moved on its pivot.

3. An earth boring machine including in combination a supporting frame, an auger tower pivotally mounted on said supporting frame, means for raising and lowering the auger in the tower, including a shaft connected to said auger tower and movable therewith, a driving shaft and connections between said driving shaft and said shaft on the auger tower, said connections including a shaft movable with respect to said driving shaft, and geared thereto to be rotated thereby; a connected gear and box 20 slideable on said movable shaft, said box being connected to the shaft on said auger tower and said last mentioned gear being geared to said shaft on the auger tower whereby said auger tower may be moved on its pivot without disturbing the driving connection with said driving shaft.

4. An earth boring machine including in combination a supporting frame, an auger tower pivotally mounted on said supporting frame, means for raising and lowering the auger in said tower including a chain and sprocket connection for the auger, a shaft journaled in the auger tower for rotating said sprocket, a driving shaft journaled in the supporting frame, a sleeve loosely mounted on said driving shaft, another shaft journaled in said sleeve for rotation relative to said shaft and movable with respect to said driving shaft and having a geared connection therewith, and a gear movable on said other shaft having connection with the shaft on said auger tower whereby the auger tower may be moved on its pivot without breaking said driving connection.

5. An earth boring machine including in combination a supporting frame, an auger tower pivotally mounted on said supporting frame, means for raising and lowering the auger in said tower including a chain and sprocket connection for the auger, a shaft journaled in the auger tower for rotating

said sprocket, a driving shaft journaled in the supporting frame, a sleeve loosely mounted on said driving shaft and having a boss thereon, a shaft journaled in said boss and having a geared connection with said driving shaft, a connected box and gear movably mounted on said last mentioned shaft, the shaft on said auger tower being connected to said box and said last mentioned gear being operatively connected to said shaft on the auger tower, whereby the auger tower may be moved on its pivot without disturbing the driving connection.

6. An earth boring machine including in combination, a supporting frame, an auger tower pivotally mounted on said supporting frame, means for raising and lowering the auger in said tower including a chain and sprocket connection, a shaft journaled in said auger tower and extending transversely thereof and operatively connected to said sprocket, said shaft having a gear and a box on one end, a driving shaft journaled on said supporting frame having a sleeve loosely mounted thereon, said sleeve being provided with a boss, a shaft mounted to rotate in said boss, intermeshing gears on said driving shaft and said last mentioned shaft whereby the latter will be driven in any position it assumes about said driving shaft, a gear connected to said box and slidably keyed to said last mentioned shaft so that said box and said last mentioned gear will move on said last mentioned shaft when the auger tower is turned on its pivot without breaking the driving connection.

7. An earth boring machine including in combination a supporting frame, an auger tower pivotally mounted on said supporting frame, means for raising and lowering the auger in said auger tower including a driving shaft on said supporting frame, a shaft mounted on said auger tower, and another shaft having a permanent driving connection with said driving shaft but movable about the axis of the same as the center, said other shaft having a movable driving connection with the shaft on the auger tower.

In testimony whereof I hereunto subscribed my name.

WILLIAM E. MOORE.
